(57) **CLAIM**

The ornamental design for a magnifier, as shown and described.

DESCRIPTION

FIG. 1 is a top, front, right side perspective view of a magnifier;

FIG. 2 is a front elevation view of FIG. 1;

FIG. 3 is a rear elevation view of FIG. 1;

FIG. 4 is a left side elevation view of FIG. 1;

FIG. 5 is a right side elevation view of FIG. 1;

FIG. 6 is a top plan view of FIG. 1; and,

FIG. 7 is a bottom plan view of FIG. 1.

The evenly dashed broken lines show portions of the article that form no part of the claimed design. The unevenly dashed broken lines represent boundaries of the claimed design and form no part of the claimed design.
